UNITED STATES PATENT OFFICE.

JOHN M. THAYER, OF AMERICUS, GEORGIA.

DESIGN FOR A COMBINED INKSTAND AND PEN-RACK.

48,802.

Specification for Design.

Patented Mar. 28, 1916.

Application filed February 10, 1915. Serial No. 7,363. Term of patent 3½ years.

To all whom it may concern:

Be it known that I, JOHN M. THAYER, a citizen of the United States, residing at Americus, in the county of Sumter and State of Georgia, have invented a new, original, and ornamental Design for a Combined Inkstand and Pen-Rack, of which the following is a specification, reference being had to the accompanying drawing, forming part thereof.

The figure is a front elevation of a combined inkstand and pen rack showing my new design.

I claim:—

The ornamental design for a combined inkstand and pen rack, as shown.

JOHN M. THAYER.
